UNITED STATES PATENT OFFICE.

IRWIN A. SEIDERS, OF READING, PENNSYLVANIA.

LUBRICATOR.

Application filed July 3, 1925. Serial No. 41,239.

This invention relates to improvements in lubricators.

An object of the invention is to provide mechanism for lubricating the tire flanges of 5 railway car or locomotive wheels, to reduce the rapid wear occurring in service due to the excessive friction between unlubricated surfaces, said mechanism being arranged to operate automatically to feed lubricant to 10 the wheels when the same are in motion, and to cut off the feed when the wheels are at rest.

Another object of the invention is to provide a mechanism of this character in which 15 the feeding means include an actuating element associated with a reservoir containing lubricant, and co-operating with a flanged wheel, whereby the vibration of the wheel during its travel imparts vibratory movement to said actuating element which operates valve means to release small quantities of lubricant upon the wheel, the arrangement being such that when the actuating element is no longer vibrated as when the 20 wheel comes to rest, the flow of lubricant is automatically checked.

Another object of the invention is to provide a mechanism in which novel means are utilized for maintaining the mechanism in 30 position to be acted upon by the movement of the wheel with which it is associated, said means being arranged to yieldably maintain the mechanism in operative relation with the wheel in the plane of its movement, and 35 also in operative relation with the flange of the wheel at an angle to the plane of the movement of said wheel.

Other and further objects of the invention will more fully and clearly appear from the 40 description and claims hereinafter following.

In the drawings forming a part of this specification, Figure 1 is a fragmentary side elevation of a locomotive showing my invention in connection therewith; Figure 2 is a transverse vertical sectional view on the line 2—2 of Figure 1; Figure 3 is an enlarged vertical sectional view through the lubricating device proper, and through the 45 wheel with which it co-operates; and Figure 50 4 is a transverse sectional view of the invention on the line 4—4 of Figure 3.

Referring more particularly to the drawings, the invention is illustrated as applied 55 to a locomotive, though it is obvious that

the device may be used in connection with any other vehicle provided with wheels, and in connection with which it is desired to lubricate the tires thereof.

As shown in the drawings, 10 denotes the 60 boiler of the locomotive, 11 cross-brace or guide arms, 12 a gusset plate, 13 the frame, 14 an axle, and 15 the wheels, said wheels being provided with the usual flanges 16 which bear upon the inner sides of the track 65 17.

As shown lubricating means are provided at opposite sides of the locomotive, or other vehicle, each lubricating means being indicated as an entirety at A, and including a 70 tank or reservoir B, and a distributor C.

The tank or reservoir B on the left side of the locomotive as shown in Figure 2 is mounted on a support 19, connected by suitable means to the boiler 10, the end of the 75 support 19 projecting outwardly beyond the cylinder 18 a suitable distance, and secured to the support 19 by means of bolts 20 are spaced straps 21 and 22, such straps being arranged to accommodate the tank B associated therewith, a filling pipe and a cap for the tank being provided which projects above the support 19, as shown at 23. The tank B is provided with a conduit 123 of any suitable material, which leads to the 80 distributor C and is adapted to conduct lubricant thereto, a valve 24 being interposed between the ends of the conduit for controlling the passage of lubricant to the distributor. The lubricating means associated with the wheel upon the opposite side of the boiler 10, are identically similar to those just described, except for the provision of a slightly different bracket for supporting the tank, and the same reference 85 characters will be used to describe similar parts of such construction. The distributors C in both instances are identically similar in construction and operation, and only 90 one of the same will be described in detail 95 herein.

Each distributor C is mounted upon a supporting arm 30 having a flattened portion 30^a by which the arm is secured to an angular bracket 31 fastened to the plate or 100 diaphragm 12, said arm 30 projecting outwardly toward the adjacent wheel 15. The other end of the arm 30 is provided with a bore 32 for the reception of the shank 33 of a T-head 34, the shank being secured in pos- 105 110 115

tion by pins 35, the head of the T member 34 being provided with a socket 36, in which may be disposed the turned end 37 of a coiled spring 38 which is disposed about the body portion of the arm 30, the inner end of the spring 38 bearing against the inner face of a sleeve 39 which is loosely mounted upon the arm 30. The sleeve 39 includes an enlarged portion 40, providing a socket 10 for the threaded reception of the hollow extension 41 formed on the body portion 42 of the distributor C, the arrangement being such that the coiled spring 38 is under torsion when placed in position, as well as 15 under longitudinal compression, whereby the inner end of the spring 38 by engagement with suitable lugs 43 on the inner face of the hollow extension 41 urges the distributor in a clockwise direction, and also 20 by reason of the pressure of the spring upon the sleeve 39, urges the distributor inwardly toward the flange 16 of the wheel 15, it being noted that the tension exerted by the spring may be regulated when desired by 25 engaging the turned end 138 of the spring 38 with any one of the lugs 43.

The body portion 42 of the distributor preferably extends at right angles to the extension 41, and includes a tubular member having a chamber 42^a open at its upper end, the exterior of said end being threaded for the reception of a nipple 143, which has a bore 44 extending therethrough, the outer end portion of the nipple 143 being threaded for the reception of a connecting cap 45 forming part of the conduit 123. The opposite portion of the body member 42 is provided with a conical valve seat 46, and co-operating with the valve seat is a conical 40 valve 47, forming part of the actuating member 48, said actuating member projecting outwardly through an oil chamber 49, and through the nozzle 50, and into engagement with the wheel 15, it being noted that 45 the actuating member 48 has a loose fit with the nozzle 50 of the body portion of the distributor, and interposed between the inner end of the actuating member and the inner wall of the nipple 143 is a coiled 50 spring 51 which normally urges the actuating member 48 to projected position.

In use, the check valve 24 is operated to permit passage of the lubricant to the distributor, said lubricant passing into the 55 chamber 42^a, where the same will remain, when the wheels are at rest, due to the engagement of the conical valve with the tapered valve seat of the body portion 42, the actuating member 48 being held in contact 60 in the plane of movement of the wheel by the torsional pressure afforded by the coiled spring 38, and said actuating member being pressed inwardly against the flange 16 by means of the longitudinal pressure exerted by the spring 38 upon the sleeve 39

which is connected to the extension 41 forming part of the distributor C. When the wheel 15 is in motion, due to the vibration thereof during its travel, vibratory movement will be imparted to the actuating 70 member 48, causing the same to move the valve 47 out of and into contact with the valve seat, thereby releasing a small quantity of lubricant, which initially flows into the chamber 49, and thereafter passes out 75 of the nozzle 50 onto the wheel 15. As soon as the wheel comes to rest, the vibration ceases, permitting the valve associated with the actuating member 48 to remain in contact with the valve seat 46.

With the above described arrangement means are provided for causing the automatic flow of lubricant when the wheels are in motion, and when the wheels come to rest, to automatically check the flow of lubricant thereto, the construction being such that the distributor is held in operative engagement with the wheel in two directions by a simple and convenient arrangement of mechanism.

While I have herein shown and described what I now consider the preferred manner of carrying out my invention, the same is merely illustrative and I contemplate all changes and modifications that come within 95 the scope of the claims appended hereto.

I claim:

1. In a device of the character described, the combination with a flanged wheel; of lubricating means including a feeding device 100 arranged to feed lubricant to the periphery of said wheel, said lubricating means being disposed tangentially with reference to circumferential periphery of said wheel; and means for simultaneously yieldably urging 105 said feeding device toward said wheel in the plane of its rotation and laterally against the flange of said wheel.

2. In a device of the character described, the combination with a flanged wheel; of lubricating means including a feeding device 110 arranged to feed lubricant to the periphery of said wheel disposed for movement in a plane substantially common with the plane of rotation of said wheel; and a single spring arranged to urge said feeding device toward said wheel in the plane of 115 its rotation, and laterally against the flange of said wheel.

3. In a device of the character described, the combination with a flanged wheel; of a lubricant supply; a distributing device co-operating with said lubricant supply; means for maintaining said distributor in co-operative relation with said wheel, said means including yieldable devices exerting a combined rotational force upon said distributor in the direction of the wheel in the plane of its motion, and laterally of said 125 plane of motion and against said flange; 130

and feed means for said distributor including an actuating element yieldably urged into contact with said wheel.

4. In a device of the character described, the combination with a flanged wheel; of a lubricant supply; a distributing device co-operating with said lubricant supply; means for maintaining said distributor in co-operative relation with said wheel, said means including yieldable devices exerting a combined force upon said distributor in the direction of the wheel in the plane of its motion, and laterally of said plane of motion and against said flange; feed means for said distributor including an actuating element yieldably urged into contact with said wheel, and valve means associated with said actuating element and adapted to be opened and closed by reciprocation of said actuating element.

5. In a device of the character described, the combination with a flanged wheel; of a lubricant supply; a distributor communicating with said supply and arranged to feed lubricant to said wheel; and means for urging said distributor toward said wheel in the plane of its movement, and in the direction of said flange, said means being constructed to permit adjustment of the pressure thereof.

6. In a device of the character described, the combination with a wheel; of a source of lubricant; a distributor disposed in operative relation with said wheel, and comprising a chamber member provided with a conical valve seat; an actuating member provided with a conical valve co-operating with said valve seat, said actuating member being yieldably urged outwardly from said distributor into engagement with said wheel; and yieldable means associated with said distributor and normally urging said actuating member toward said wheel, said distributor being provided with a nozzle and a lubricant chamber beyond said valve means, said nozzle forming a loose guide for said actuating member to permit flow of lubricant therewith.

7. In a device of the character described, the combination with a flanged wheel; of a lubricant supply; a distributor arranged to feed lubricant to said wheel, said distributor being provided with an angular extension; a supporting member extending into said extension, and provided with an enlarged head; a sleeve loosely mounted on said arm and connected to said extension; and yieldable torsional and expansive means inter-

posed between said head and sleeve, and connected thereto.

8. In a device of the character described, the combination with a flanged wheel; of a lubricant supply; a distributor arranged to feed lubricant to said wheel, said distributor being provided with an angular extension; a supporting member extending into said extension, and provided with an enlarged head; a sleeve loosely mounted on said arm and connected to said extension; and yieldable torsional and expansive means interposed between said head and sleeve, and connected thereto, said resilient means being provided with an adjustable connection with the said sleeve.

9. In a device of the character described, the combination with a flanged wheel, of a source of lubricant supply; of a distributor communicating with said source of supply, said distributor being in the form of a T-casting, the stem and arm of which are provided with independent bores, the arm of said T-member having on its interior a valve seat; an actuating member slidably mounted in said arm and including a valve co-operating with said valve seat, said actuating member being yieldably urged toward said wheel, and normally maintaining said valve in closed position; a supporting arm provided with a head at its extremity extending into said hollow stem; a slideable and rotational means mounted on said supporting arm and connected with said stem; and combined expansion and torsional yieldable means interposed between the head of said supporting arm and said sleeve, and connected to said head and sleeve.

10. In a device of the character described, the combination with a railway vehicle provided with a supporting wheel; of a lubricant container; feeding means communicating with said container, said feeding means being fixedly mounted on the vehicle for supplying lubricant to the rim of said wheel, said feeding means including a movable cut-off valve mechanism for controlling the flow of the lubricant, said cut-off valve cooperating with said wheel and actuated thereby through relative vibratory movement of said wheel and fixed mounting of the feed means in all positions of said wheel while in motion.

In witness that I claim the foregoing I have hereunto subscribed my name this 26th day of June, 1925.

IRWIN A. SEIDERS.
